SAFETY FOR FIREARMS

Frederick L. Bistoff, Lockport, N. Y.

Application April 24, 1946, Serial No. 664,651

6 Claims. (Cl. 42—70)

1.

This invention relates to a safety for firearms and more particularly to a safety for a portable shoulder fire arm.

A number of conventional rifles are provided with some form of a so-called "trigger guard" safety, i. e., a safety device to prevent unintentional firing of the gun, which is arranged on or adjacent the trigger guard. This type of safety is not fully satisfactory because the safety is not well positioned and is slow to move and awkward for fast shooting or with cold hands. When big game is jumped or birds are raised from cover, it is desirable to have a safety which can be thrown off quickly without effort and without requiring the operator to take his eyes off the game. The so-called "shotgun safety" is most desired for this purpose, i. e., a safety device to prevent unintentional firing of the gun having a thumb slide arranged on top of the grip of the firearm.

It is therefore the principal object of the present invention to provide a safety for firearms of the "shotgun safety" type which is readily accessible and manually quick and easy to operate.

Another object is to provide such a safety which is manually operated to set the safety in either its "off" or "on" position and which will remain in either of its set positions until reset.

Another object is to provide such a safety which is simple and efficient in construction and not liable to require repairs.

A further aim is to provide such a safety for inexpensive adaptation to conventional types of firearms necessitating only a minimum of new parts and remodeling of the firearm.

Still other advantages will be readily apparent from the following description and accompanying drawings wherein:

Figure 1 is a fragmentary vertical longitudinal section through a conventional type of lever action rifle and showing such rifle provided with the safety device forming the subject of the present invention.

Figure 2 is a view similar to Figure 1 and showing the parts in a different condition.

Figure 3 is a fragmentary top plan view of the rifle shown in Figure 1.

Figure 4 is a vertical transverse section taken along the line 4—4, Figure 1.

Figure 5 is a horizontal transverse section taken along line 5—5, Figure 1.

Figure 6 is a horizontal transverse section taken along line 6—6, Figure 4.

The safety device of the present invention may be either incorporated as original equipment in

the firearm, as is shown in the accompanying drawings, or the firearm may be adapted to receive the safety device.

In Fig. 1 is shown a conventional type of lever action rifle having a frame including upper and lower tangs 10 and 11, respectively, a trigger 12 pivotally mounted on the lower tang 11 and being operatively connected to a sear 13 which in turn operatively cooperates with a breech block assembly indicated generally by the numeral 14, a trigger spring 15 secured at its rear end to the lower tang 11 and having its forward end engaging the trigger 12, a cocking lever 16 pivotally mounted on the lower tang 11, a shoulder stock 17 of usual form and being centrally and vertically recessed at its front end to provide side portions 18—18 which embrace the sides of the upper and lower tangs 10 and 11, and a long bolt 19 arranged in a horizontal longitudinal bore in the stock 17 and threadedly engaging with the lower tang 11 thereby to positively connect the stock to the frame of the rifle.

The safety device forming the subject of the present invention includes a safety slide member 20 rectangular in cross-section and arranged in a groove 21 provided in the lower tang 11 so as to be forwardly and rearwardly slidable therein, such movement in either direction being limited by the respective end wall of a slot 22 provided in the member 20 contacting a stationary transverse pin 23 mounted in the lower tang 11. The front end of the slide member 20 is adapted to engage a flat 24 on the trigger 12. A laterally extending lug 25 is arranged on the cocking lever 16 at a point immediately adjacent and in rear of the trigger 12. This lug 25 on its underside is adapted to be engaged by a finger 26 arranged on the slide member 20. Thus, when the safety slide member 20 is in the locked or "safe on" position shown in Fig. 1, the front end of the member engages the flat 24 and prevents the trigger 12 from being operatively moved in a clockwise direction and thereby preventing the firing mechanism of the rifle from being actuated, and at the same time the finger 26 engages the lug 25 and thus prevents the cocking lever from being rotated in a counter-clockwise direction.

Means are provided for actuating the safety slide member 20 from the top of the grip which include a manually operated actuator or thumb slide 27 projecting upwardly through a longitudinally elongated slot 28 in the upper tang 10 so as to be longitudinally slidable therein and is shown as having a head arranged on the outside of the upper tang and manually movable

by the thumb or other finger of the operator as desired. The part of the thumb slide 27 arranged below the upper tang 10 is shown as being offset to the rear and provided with a downwardly projecting extension having a transverse slot 29. The slot 29 receives a transverse pin 30 carried by the upper end of a walking beam member or lever 31 which is pivotally mounted intermediate its ends on a pivot pin or screw 32 which is carried by a support 33. The support 33 is in the form of an L-shaped bracket which is secured to the lower tang 11 by a screw 34. As best shown in Fig. 4, the lever 31 is provided with a bushing 35 through which the screw 32 extends, the inner end of this screw threadedly engaging with the support 33, although any other suitable means for mounting the lever 31 on the support 33 or other part of the frame may be employed.

Referring to Fig. 4, the lower part of the lever 31 is offset laterally outwardly beginning immediately below its pivotal mounting and thence continues straight downwardly through a recess or undercut 36 provided in the right side of the lower tang 11, the extreme lower end of the lever being curved inwardly and bifurcated so that the fingers 37—37 formed thereby straddle extension 38 which extends laterally outwardly from the safety slide member 20. The inner opposing edges of the fingers 37 are slightly convex.

Detent means are provided for yieldingly retaining the thumb slide 27 in either of its two adjusted positions and for this purpose, referring to Fig. 6, the upper tang 10 is provided with a transverse horizontal hole 39 which leads from the right side of the upper tang to the slot 28 and in which are arranged a follower 40 constantly urged inwardly by a spring 41 and backed up by a retainer plug 42 which screws into the outer end of the hole 39. The inner end of the follower 40 has a round nose which engages either a front or rear inclined cam surface 43 and 44, respectively, provided in a groove 45 on the right side of that portion of the thumb slide 27 which is arranged in the slot 28. The cam surfaces 43 and 44 are reversely inclined with their opposing vertical edges, joining at an apex as shown in Fig. 6 and the follower 40 engages the cam surface 43 when the thumb slide 27 is in its rear position, as limited by the thumb slide striking the rear transverse wall of the slot 28. When the thumb slide is pushed forwardly to the broken line position shown in Fig. 6, the front cam surface 43 forces the follower 40 farther into the hole 39, thereby further compressing the spring 41 until the follower passes the vertical apex of the cam surfaces 43 and 44 and thereafter the spring 39 forces the follower 40 out of the hole 39 to keep the follower in engagement with the rear cam surface 44, the thumb slide 27 continuing to move until the front end strikes the front transverse wall of the slot 28. It will be noted that when the thumb slide 27 is moved in either direction from one position to the other the spring loaded follower 40 cooperates with the respective cam surface 43 or 44 to hold the thumb slide in its adjusted position.

Instead of providing such detent means in connection with the thumb slide 27, detent means can be provided in connection with either the safety slide member 20 or the lever 31, the purpose being in any arrangement to yieldingly retain the member 20 in its forward operative or rearward inoperative position.

The safety is "on" in Fig. 1. The thumb slide is in its rearmost position and it will be noted

that the safety slide member is in its forward position and engages the flat 24 on the trigger 12 and the finger 26 of said member engages the lug 25 formed on the cocking lever 16. Neither the trigger nor the cocking lever can be operated. To move the safety to the "off" position, the thumb slide 27 is pushed forwardly to its most forward position, as shown in Fig. 2, and as previously described herein the detent means will tend to maintain the thumb slide in this position. The forward movement of the thumb slide causes the slot 29 therein to shift the pin 30 and thereby rotates the lever 31 in a clockwise direction about the pivot pin 32. The lower end of the lever 31 thus moves the safety slide member 20 rearwardly in the groove 21 thereby removing the front end of the member from the flat 24 and disengaging the finger 26 and the lug 25. The trigger is then free to be operated to actuate the firing mechanism of the rifle and the cocking lever is free to be operated, as is shown in Fig. 2.

If the conventional type of lever action rifle shown in the accompanying drawings and described hereinabove does not have the safety device forming the subject of the present invention incorporated therein as original equipment, the rifle can easily be adapted for such safety device. If the upper tang 10 is not long enough to mount the thumb slide 27, an upper tang extension (not shown) can be connected to the tang and additionally supported by extending the support 33 upwardly and connecting the same to the upper tang extension, the vertical recess 35 in the front end of the stock 17 being further hollowed out to accommodate the parts. If such rifle has the safety slide member 20 already incorporated therein with some form of detent means to tend to maintain the member in either its forward or rear position, these detent means can be easily removed and the slide member adapted to operate in the manner described hereinabove. Further, the undercut 36 can be readily made in the lower tang 11 if not already present and the modified support 31 can replace a breech block assembly stop that may have been incorporated as an original part of the rifle.

Changes, variations and modifications to the specific form of the present invention shown and described herein are possible and it is not intended to limit the invention to the form shown except as may be defined in the following claims.

I claim:

1. In a shoulder firearm having a frame including upper and lower tangs, a shoulder stock extending rearwardly from said tangs and having a grip portion adjacent said tangs, a trigger and cocking lever pivotally mounted on said lower tang, a safety slide member arranged on said lower tang and slideable forwardly to engage said trigger and cocking lever thereby to prevent their operation and slideable rearwardly to disengage said trigger and cocking lever thereby to permit them to be operated, and a laterally extending lug on said safety slide member and arranged below said lower tang, the combination therewith of means for operating said safety slide member comprising a lever arranged in a slot provided in one side of said lower tang and extending below and above said lower tang, the lower extremity of said lever being operatively connected to said lug on said safety slide member, a thumb piece forwardly and rearwardly slideably arranged on said upper tang immediately in advance of said grip portion, means op-

eratively connecting the upper extremity of said lever to said thumb piece, and means pivotally supporting said lever whereby movement of said thumb piece in either direction effects movement of said safety slide member in the opposite direction.

2. In a shoulder firearm having a frame including upper and lower tangs, a shoulder stock extending rearwardly from said tangs and having a grip portion adjacent said tangs, a trigger and cocking lever pivotally mounted on said lower tang, a safety slide member arranged on said lower tang and slideable forwardly to engage said trigger and cocking lever thereby to prevent their operation and slideable rearwardly to disengage said trigger and cocking lever thereby to permit them to be operated, and a laterally extending lug on said safety slide member and arranged below said lower tang, the combination therewith of means for operating said safety slide member comprising a lever arranged in a slot provided in one side of said lower tang and extending below and above said lower tang, the lower extremity of said lever being notched to receive said lug on said safety slide member, a thumb piece forwardly and rearwardly slideably arranged on said upper tang immediately in advance of said grip portion, a pin and slot connection between the upper extremity of said lever and said thumb piece, and means pivotally mounting said lever on one of said tangs so as to be pivotable about an axis extending transversely of said lever and intermediate said extremities thereof whereby movement of said thumb piece in either direction effects movement of said safety slide member in the opposite direction.

3. In a shoulder firearm having a frame including upper and lower tangs, a shoulder stock extending rearwardly from said tangs and having a grip portion adjacent said tangs, a trigger and cocking lever pivotally mounted on said lower tang, a safety slide member arranged on said lower tang and slideable forwardly to engage said trigger and cocking lever thereby to prevent their operation and slideable rearwardly to disengage said trigger and cocking lever thereby to permit them to be operated, and a laterally extending lug on said safety slide member and arranged below said lower tang, the combination therewith of means for operating said safety slide member comprising a lever arranged in a slot provided in one side of said lower tang and extending below and above said lower tang, the lower extremity of said lever being operatively connected to said lug on said safety slide member, a thumb piece forwardly and rearwardly slideably arranged on said upper tang immediately in advance of said grip portion, means operatively connecting the upper extremity of said lever to said thumb piece, means pivotally supporting said lever so as to be pivotable about an axis extending transversely of said lever and intermediate said extremities thereof whereby forward movement of said thumb piece effects rearward movement of said safety slide member and vice versa, and means yieldingly urging said thumb piece toward either its extreme forward or extreme rearward position.

4. In a shoulder firearm having a frame including upper and lower tangs, a shoulder stock extending rearwardly from said tangs and having a grip portion adjacent said tangs, a trigger and cocking lever pivotally mounted on said lower tang, a safety slide member arranged on

said lower tang and slideable forwardly to engage said trigger and cocking lever thereby to prevent their operation and slideable rearwardly to disengage said trigger and cocking lever thereby to permit them to be operated, and a laterally extending lug on said safety slide member and arranged below said lower tang, the combination therewith of means for operating said safety slide member comprising a lever arranged in a slot provided in one side of said lower tang and extending below and above said lower tang, the lower extremity of said lever being operatively connected to said lug on said safety slide member, a thumb piece forwardly and rearwardly slideably arranged on said upper tang immediately in advance of said grip portion, means operatively connecting the upper extremity of said lever to said thumb piece, means pivotally supporting said lever so as to be pivotable about an axis extending transversely of said lever and intermediate said extremities thereof whereby forward movement of said thumb piece effects rearward movement of said safety slide member and vice versa, and means yieldingly urging said thumb piece toward either its extreme forward or extreme rearward position, comprising a salient cam on one lateral side of said thumb piece having reversely inclined contiguous vertical cam surfaces, a follower engaging said cam and mounting on said upper tang for reciprocal movement in a direction transverse to the direction of movement and spring means constantly urging said follower into engagement with said cam.

5. In a shoulder firearm having a frame including upper and lower tangs, a shoulder stock extending rearwardly from said tangs and having a grip portion adjacent said tangs, a trigger and cocking lever pivotally mounted on said lower tang, and a safety slide member arranged on said lower tang and slideable forwardly to engage said trigger and cocking lever thereby to prevent their operation and slideable rearwardly to disengage said trigger and cocking lever thereby to permit them to be operated, the combination therewith of means for operating said safety slide member comprising a bracket mounted on said lower tang and having an upstanding arm, a lever arranged laterally of one side of said upstanding arm and having its extremities arranged adjacent said upper and lower tangs, means pivotally mounting said lever intermediate its ends on the upper end of said upstanding arm, a thumb piece forwardly and rearwardly slideably arranged on said upper tang immediately in advance of said grip portion, means operatively connecting the upper extremity of said lever to said thumb piece and means operatively connecting the lower extremity of said lever to said safety slide member whereby movement of said thumb piece in either direction operates to swing said lever and thereby move said safety slide member in the opposite direction.

6. The combination of safety mechanism with a rifle of the type comprising a frame including upper and lower tangs, a shoulder stock extending rearwardly from said tangs and having a grip portion adjacent said tangs, a trigger pivoted on said lower tang and having a rearward projection, a cocking lever pivoted on said lower tang and having a laterally extending lug arranged adjacent said rearward projection when said trigger and cocking lever are in their inoperative positions, said safety mechanism comprising a bracket mounted on said lower tang

and having an upstanding arm, a lever arranged laterally of one side of said upstanding arm, means pivotally mounting said lever intermediate its ends on the upper end of said upstanding arm, a thumb piece forwardly and rearwardly slideably arranged on the top side of said rifle at said grip portion, means operatively connecting the upper end of said lever to said thumb piece, and elements operatively associated with the lower end of said lever and movable thereby into engagement with said rearward projection and lug to prevent operation of said trigger and cocking lever and also movable by said lever out of engagement with said rearward projection and lug to permit operation of said trigger and cocking lever whereby movement of said thumb piece in either direction operates to swing said lever and move said elements in the opposite direction.
